UNITED STATES PATENT OFFICE.

ALEXANDRE GENAILLE, OF NEW YORK, N. Y., ASSIGNOR TO CARTIER, INC., OF NEW YORK, N. Y., A CORPORATION OF NEW YORK.

BRACELET.

1,419,370.

Specification of Letters Patent. Patented June 13, 1922.

Application filed February 27, 1920. Serial No. 361,777.

To all whom it may concern:

Be it known that I, ALEXANDRE GENAILLE, a citizen of France, residing at New York city, borough of Manhattan, county and 5 State of New York, have invented a certain new and useful Bracelet, of which the following is a specification.

This invention is a bracelet adapted to be worn by ladies, solely as an article of personal adornment, and the object of the invention is a bracelet possessing a neat, attractive and aesthetic appearance, capable of ready adjustment to a wide range of 10 wrist sizes, and yet of a simple and durable 15 construction, and capable of expeditious and economical manufacture.

In its preferred, practical form, the invention embodies a flexible member, which may consist of a woven silken cord, a precious metal chain or cable or a jointed metallic construction of the precious metals. The 20 ends of the flexible member are tipped with suitable ornamental pendants, formed of metal, jewels, or a combination of both, and the intermediate portions of the flexible member 25 are passed twice through a suitable ornamental slide, whereby the flexible member is formed into a loop adapted to encircle the wrist. The slide may be manipulated 30 to vary the size of the loop, so that it will properly fit the wrist of the wearer.

Features of the invention, other than those specified, will be apparent from the herein-after detailed description and claims, when 35 read in conjunction with the accompanying drawings.

The drawings illustrate one practical embodiment of the invention, but the construction therein shown is to be understood as 40 illustrative, only, and not as defining the limits of the invention.

Figure 1 illustrates a bracelet embodying the present invention positioned upon the wrist of a wearer; and,

45 Figure 2 shows the bracelet removed from the wrist.

The bracelet embodies a flexible tension member A, here shown in the form of a woven cord, and, in practice, this may be a 50 silken or metal cord, or cable, or said member may be made up of a plurality of links, or other metallic elements, suitably, flexibly associated with one another, so as to conform to the contour of the wrist. The two ends

of the flexible member A are passed through 55 a slide B and are tipped with suitable ornaments C. The slide B, while shown of simple, spherical contour, may partake of any desired shape, and may be adorned with 60 jewels or other form of ornament in conformity with the taste of the designer, and the members C may be similarly constructed and adorned, but they are preferably made of sufficient weight to hold the flexible member taut. In practice, it is found that if 65 the members C are slightly weighted, they serve to hold the slide B in a position to maintain the loop of the bracelet in proper conformity with the curves of the wrist.

It has heretofore been suggested that 70 pocketbooks, fans and other articles be secured to the wrists of users by means of loops formed in a flexible member, but these prior devices have been intended for entirely different uses and functions from the 75 purely ornamental purposes inherent in the bracelet of this invention. Moreover, they were not intended for use as bracelets, and their size and structural characteristics, as well as their design, would preclude their 80 employment for this purpose.

It will be understood that the specific structure described may be modified as to details, more especially in formal respects, without departing from the spirit and substance of the invention, the scope of which is commensurate with the appended claims.

Having thus fully described the invention, what I claim as new and desire to secure by Letters Patent is:

1. An article of jewelry consisting of a bracelet embodying a flexible member, a slide through which the flexible member is passed to form a portion of said member into a loop adapted to embrace the wrist of 95 a wearer, said loop being maintained in conformity with the wrist by the slide, and a separate member associated with each end of the flexible member to preclude such ends from being withdrawn from the slide. 100

2. An article of jewelry consisting of a bracelet embodying a flexible member, a slide through which the flexible member is passed to form a portion intermediate the ends thereof into a loop adapted to embrace 105 the wrist of a wearer, and weights secured to the ends of the flexible member and adapted to automatically maintain the slide in a posi-

tion to cause the intermediate portion of the flexible member to properly fit the wrist.

3. An article of jewelry consisting of a bracelet embodying a slide, a flexible cord passed twice through said slide to form a loop adapted to embrace the wrist of a wearer, and a separate ornamental member secured to each end of the cord, to preclude

such ends from being withdrawn from the slide.

In testimony whereof, I have signed my name to this specification.

ALEXANDRE GENAILLE.

Witness:

E. F. PROPER.
